UNITED STATES PATENT OFFICE.

WILLIAM CLIFFORD MAYNARD, OF MIAMI, FLORIDA.

TERMINAL CONNECTOR.

1,190,931.

Specification of Letters Patent. Patented July 11, 1916.

Application filed December 1, 1915. Serial No. 64,505.

To all whom it may concern:

Be it known that I, WILLIAM C. MAYNARD, a citizen of the United States, and a resident of Miami, in the county of Dade and State of Florida, have invented a new and Improved Terminal Connector, of which the following is a full, clear, and exact description.

My invention, while applicable for use in connecting a conductor to the terminals of different electrical apparatus, is more particularly designed for connecting the conductor with a battery terminal. With spring clamps usually employed, the same is either carried as an attachment to the terminal or to the conductor and in either case, the circuit is established through the connector. An important objection to this type of connector is that it depends on the conductivity of the connector and on the proper connection thereof with the conductor and with the terminal so that a defective connection is liable to result either with the one or the other.

My invention provides a connector in which the electric circuit is established directly between the conductor and terminal by direct contact thereof without the intermediary of the connector as a conducting medium, the arrangement being such that the sole office of the connector is to clamp the conductor and terminal in direct contact with each other.

The invention has in view, also, to enable the connection or disconnection of the terminal and conductor to be effected with facility and despatch as well as to insure a good metallic contact therebetween.

The invention will particularly be explained in the specific description following.

Reference is to be had to the accompanying drawings forming part of this specification in which similar reference characters indicate the corresponding parts in all the views.

Figure 1 is a side elevation of a terminal connector embodying my invention, showing the same applied to a battery terminal and a conductor; Fig. 2 is a rear perspective view of the connector device; and Fig. 3 is a front perspective view of said device.

In the illustrated example, the numeral 10 indicates the conductor which may involve a single wire or a multiple of wires,

the numeral 11 indicating a threaded terminal secured to a battery element 12 by a nut 13 as usual.

My improved connector device, designated generally by the numeral 14, includes an element 15 formed with an oblong opening 16, through which the battery terminal 11 is adapted to be entered axially. The connector is preferably made of sheet metal and the element 15 will, when applied to the battery terminal 11, be disposed approximately parallel with the battery element 12. The element 15 terminates at one end in a returned flange 17 preferably curved transversely to constitute what may, in effect, be considered a broad hook, which is adapted to receive and seat the end of the conductor 10 in a direction transverse to the axis of the terminal 11. The opening 16 extends adjacent to the conductor seat 17 so that, with the conductor 10 lying thereon, it will be adjacent to and may make direct contact with the threaded side of the terminal 11.

The element 15, and a co-acting clamp element 18, are formed respectively at the opposite ends of a bowed spring presenting an arm 19 integral with the element 15 and extending from that end of said element 15 opposite the conductor seat 17, said arm 19 being return bent to produce the arm 18 and dispose the free end of the latter toward and adjacent to the element 15 and therefore, adjacent to the oblong slot 16 through which the battery terminal is entered. The free end of the resilient arm 18 is preferably formed with a flange 20 at approximately right angles to said resilient arm and lying substantially parallel with the element 15 to present the edge of the flange laterally to the terminal 11.

In practice, the resiliency of the clamp arms 18, 19 tends to move the conductor seat 17 and the flanged end 20 of the arm 18 toward each other, the said flanged end 20 moving over the opening 16. With the battery terminal 11 and the conductor 10 in place, the resilient clamp members will thus press the said conductor and terminal against each other in crossed relation, the clamp elements bearing respectively against the battery terminal and the conductor, with the conductor in direct and firm contact with the threaded side of the terminal.

The opening 16 extends to and partially

- into the curved flange 17 and the free edge of said flange is preferably formed with a concave depression 20. By this arrangement the lateral pressure exerted on the terminal 5 11 toward the conductor 10 will unfailingly make good contact therewith without interference from the flange 17 since the terminal is permitted to closely approach the bottom of the said flange.
- 10 It is to be observed that the electric current is established directly between the conductor and terminal without being required to pass through the connector device.
- Having thus described my invention I 15 claim as new, and desire to secure by Letters Patent:
1. A connector of the class described including a seat member to receive a conductor wire, there being an opening in the connector adjacent to and transversely of the 20 said seat member, for the entrance axially therethrough of a terminal in a direction transversely of the seat, and a spring-pressed clamp element having a movement 25 toward the seat member, across said opening, to engage the terminal and draw the conductor and terminal in direct contact with each other in crossed relation.
2. An electrical terminal connector having 30 two opposed resilient clamp elements movable relatively to each other, one of which presents a member adapted to receive a conductor and a terminal disposed in crossed relation between said clamp elements, the 35 said elements acting to press the conductor and terminal in direct contact for the direct passage of the current without the intermediary of the connector as a conducting medium.
3. In a device of the class described, in 40 combination; a conductor, a connector formed with a resilient arm having a member on which the said conductor seats and formed with an opening adjacent to said 45 member, a terminal extending axially through said opening across the conductor and in direct contact therewith, and a second resilient arm on said connector bearing against the terminal adjacent to said opening at the opposite side of the terminal from 50 the conductor, said arms acting to press the

conductor and terminal directly against each other.

4. A terminal connector including an element having an opening extending therethrough adapted to receive a terminal, the 55 said element being formed at a side thereof adjacent to one end of said opening with a laterally turned flange constituting a conductor seat, and a resilient clamp element having 60 a free end adjacent to the said opening and movable to and from the said flange across the said opening.

5. A terminal connector comprising a strip of sheet metal bent to form a bowed 65 spring, one arm of which presents a member formed with an oblong opening therein, the free end of said member being returned in the form of a flange curved in cross section and constituting a seat for a conductor, said 70 opening being adapted to receive a terminal transversely of said seat, the other arm of the spring being disposed in the direction of the member having the opening, the free end of the second arm being adjacent to the 75 said opening and having its terminal bent toward the curved flange.

6. A terminal connector comprising a strip of sheet metal bent to form a bowed 80 spring, one arm of which presents a member formed with an oblong opening therein, the free end of said member being returned in the form of a flange curved in cross section and constituting a seat for a conductor, said 85 opening being adapted to receive a terminal transversely of said seat, the other arm of the spring being disposed in the direction of the member having the opening, the free end of the second arm being adjacent to the said opening and having its terminal bent 90 toward the curved flange, said opening extending into the curved flange and the edge of the curved flange having a depression opposite said opening.

In testimony whereof I have signed my 95 name to this specification in the presence of two subscribing witnesses.

WILLIAM CLIFFORD MAYNARD.
